UNITED STATES PATENT OFFICE.

PHINEAS E. MERRIHEW, OF FAIRHAVEN, MASSACHUSETTS.

CAR-COUPING.

SPECIFICATION forming part of Letters Patent No. 274,511, dated March 27, 1883.

Application filed January 30, 1883. (No model.)

To all whom it may concern:

Be it known that I, PHINEAS E. MERRIHEW, of Fairhaven, in the county of Bristol and State of Massachusetts, have invented certain new and useful Improvements in Car-Couplings; and I do hereby declare that the following is a full, clear, and exact description thereof, reference being had to the accompanying drawings, and to the letters of reference marked thereon, which form a part of this specification.

This invention has for its object to so arrange a draw-bar head that it will retain the features for connecting with a common link-and-pin coupling of an adjoining car, and to be provided with a device of simple and durable construction by which the cars will automatically couple or can be uncoupled without stepping between the cars.

Therefore my invention consists of the novel devices and combinations of devices herein-after described and specifically claimed.

In the accompanying drawings, Figure 1 represents an elevation of one end of a car that has my coupling device; Fig. 2, a longitudinal vertical section of the draw-bar and coupling link and pin in position after uncoupling, and Fig. 3 a similar section of the same in position after coupling. Fig. 4 is a plan of the draw-bar head and coupling device, and Fig. 5 a cross-section of the draw-bar on line *xx*.

Corresponding letters in the several figures of the drawings designate like parts.

A denotes the bumper or draw-bar head having a funnel-shaped mouth, *a*, with an oblong opening for the link *B*, and a vertical hole for the coupling-pin *C*, all of which is of any usual construction. Back of the coupling-pin hole the head *A* is vertically slotted for a block, *D*, that has a free vertical and longitudinal movement therein. This block *D* is flattened out at top and bottom ends, where it projects through the slots of head *A* and is laterally contracted again at its upper portion to provide shoulders *b*, while in its upper extremity is formed an eye or loop, *c*. Through this loop *c* is projected the hook-shaped crank *E* of a shaft, *F*, which is transversely pivoted against the end of the car-body, and has to its ends curved cranks *d*, by which the shaft *F* can be turned from either side of the car for raising or lowering the block *D*. Upon the rear portion of head *A* are secured two eye-lugs, *e*, between which is piv-

oted an arm, *f*, that is slotted from its pivotal end to pass over block *D* and to rest upon the shoulders *b* of same, and at its forward or swinging end such arm is bifurcated for embracing and supporting the coupling-pin *C* from under its collar in a manner that, with lifting-block *D*, the arm *f* is swung upward, which again will raise the coupling-pin *C*. The middle portion of block *D*, that is inside of head *A* and projects forward close to the coupling-pin holes, is transversely concaved in its center, and is vertically grooved out for inserting a link, *h*, that has an eye in its upper end for pivotally suspending it to a pin passed through the slotted top wall of head *A*. This link *h* is slotted vertically, and is coupled to block *D* inside of the groove of same by a pin, *i*, passed through a hole in such block and through the slot in link *h*. The link *h* has a toe, *j*, that projects forward from out the block *D*, for forming a step for the point of the coupling-pin *C* to be supported thereon before the cars are to be coupled. The bumper or coupling head *A* forms a solid part of draw-bar, *H*, the forward end of which is bored out longitudinally to form a socket for a spiral spring *m*, and a guide for push-rod *n*, which latter, by the pressure of spring *m*, forces the block *D* forward in head *A* toward the mouth of the same. With lifting-pin *C* the block *D* will be pushed forward by spring *m*, and will swing the link *h* forward for the toe *j* to catch under the point of such pin and to hold it on its elevated position, as shown in Fig. 2, and as soon as link *B* of the car to be coupled enters the mouth of head *A* and pushes the block *D* rearward the link *h* will be swung backward until the toe *j* releases the pin *C*, which now will drop and couple the link, as shown in Fig. 3.

For either uncoupling the cars or for raising the pin *C* to couple the cars the shaft *F* is turned from either side of the car by one of its cranks *d*, when the crank *E* will lift block *D*, which again will turn the arm *f*, that will raise the coupling-pin *C* until its point is elevated above toe *j* of link *h*, when the block *D* will move forward, swinging such link to project its toe *j*, that will prop the pin *C* and hold it in readiness for coupling the car again.

In the rear end of the draw-bar *H* is formed a rectangular loop, *o*, through which are placed transversely two channel-bars, *p*, that have in-

terposed two spiral springs, *q*. The ends of channel-bars *p* are guided in channel-bars *r* that are secured against the sides of the floor-beams *K* of the car-body, and are provided 5 with suitable stops for bars *p* to shoulder against in one direction in such a manner that by either pushing or pulling the draw-bar the spiral springs *q* will be compressed.

L is a cylinder secured under the car-body, 10 and *M* a piston that is fitted snugly therein, the rod *s* of which is rigidly secured to the end of the draw-bar. With a momentous heavy concussion of the cars the air captured in the cylinder *L* by piston *M* will be compressed 15 and will form a cushion that will relieve the springs *q*.

As will be noticed, the device thus shown does not derange the draw-bar head for connecting with any common car-coupling and 20 has the advantage to be self-operating, for coupling the cars, while for uncoupling no person is required to step between the cars and endanger his life, and the construction and arrangement of the operating parts are very simple and durable, and not liable to get out of 25 order.

What I claim is—

1. A car-coupling consisting of draw-bar

head *A*, having flaring mouth *a* and hole for coupling-pin *C*, and being provided with swinging link *h*, having toe *j*, with movable block *D*, and with swinging arm *f*, all substantially as set forth, to operate as specified. 30

2. A car-coupling consisting of draw-bar head *A*, having flaring mouth *a* and hole for coupling-pin *C*, and being provided with swinging link *h*, having toe *j*, with movable block *D*, spring *m*, and push-bar *n*, all constructed and arranged substantially as set forth, to operate as specified. 35

3. A car-coupling consisting of draw-bar head *A*, having flaring mouth *a* and hole for coupling-pin *C*, and being provided with swinging link *h*, having toe *j*, with movable block *D*, swinging arm *f*, spring *m*, and push-rod *n*, in 40 combination with shaft *F*, having cranks *E* and *d*, the whole being constructed and arranged to operate substantially as described and shown. 45

In testimony that I claim the foregoing as 50 my invention I affix my signature in presence of two witnesses.

PHINEAS E. MERRIHEW.
